UNITED STATES PATENT OFFICE

LEWIS F. BETTS, OF MORTON, PENNSYLVANIA, ASSIGNOR TO JOHN H. IRWIN,
OF SAME PLACE, AND ROBERT E. DIETZ, OF NEW YORK, N. Y.

STOVE.

SPECIFICATION forming part of Letters Patent No. 247,154, dated September 20, 1881.

Application filed March 21, 1881. (No model.)

To all whom it may concern:

Be it known that I, LEWIS F. BETTS, of Morton, in the county of Delaware and State of Pennsylvania, have invented certain new and useful Improvements in Stoves, of which the following is a full, clear, and exact description, reference being had to the accompanying drawings, and to the letters of reference marked thereon.

10 My invention has special relation to that class of stoves used for domestic purposes wherein hydrocarbon oils are employed as fuel, and in which the escape for the products of combustion is located at that part of the structure most remote from the source of heat or point of ignition, and has for its object the production of an effective and simple device, in which the arrangement of constituent parts is such that the air for the support of combustion is admitted to the burners through an inlet or inlets in close proximity thereto, but in such manner that the supply will be steady and uniform, in order to promote thorough and perfect combustion.

25 To accomplish this, my invention consists, essentially, in surrounding the burners with a device for regulating the supply of air thereto, the discharge-opening at the extremity of the passage for the heated products of combustion being so arranged as to expedite their outflow, thereby rapidly drawing in a supply of fresh air to the burners to feed the flame; and my invention consists in certain novel and useful combinations or arrangements of parts and 35 peculiarities of construction and operation, all of which will be hereinafter first fully described, and then pointed out in the claims.

In the drawings, Figure 1 is a side elevation and partial section of one form of stove constructed in accordance with my improvements, showing one mode of supplying air to the burners. Fig. 2 is a plan view of the oil-pot and burners employed in the stove shown in Fig. 1. Fig. 3 is side elevation and partial section of 40 a double stove. Fig. 4 is an enlarged sectional view of the burner shown in Fig. 1, illustrating the arrangement of the parts.

Like letters of reference, wherever they occur, indicate corresponding parts in all the figures,

A is the base of the stove, constructed of 50 cast-iron or any other suitable material.

B is the oil pot or reservoir, extending a part of or the entire length of the stove. Said oil-pot may be formed of tin or other preferred material, and secured to the base A, or wholly 55 or in part cast therewith, forming a portion of the same.

C are burners of any approved style, having proper connection with the oil-pot.

E is a chimney surrounding the burners, and 60 extending to sufficient height thereabove to insure perfect and complete combustion.

D is the top plate, perforated with any desired number of utensil-holes, said plate being located upon a base, D', of sufficient depth to 65 permit the bottoms of cooking utensils to extend a distance below the top plate D, and cast in such manner as, with plate D, to form a confined passage for the heated products of combustion from chimney E to the exit E', 70 provided for the same. The top of the stove may be firmly held in place upon the chimney by means of suitable rods extending through the chimney from plate D to the base of the stove, or in any other preferred manner.

75 F is a standard supporting the other extremity of the stove top and base D'.

E' is the outlet for the products of combustion, the same being so arranged that passing currents of air will serve to increase the outflow, and from its peculiar construction any 80 possibility of currents entering the outlet and causing a back-draft is obviated.

In Fig. 1 is shown a stove wherein the air for the support of combustion is supplied directly to the burners from a point upon or near a level with the top of the wick-tubes.

b is a plate surrounding the wick-tubes, upon which rests chimney E. The edges of this plate are turned downwardly at each side, leaving an open passage thereunder to the burners. Surrounding the burners is a jacket, H, placed at a distance from chimney E and plate b. Said jacket extends from the oil-pot or from a plate, b', located a short distance thereabove, to a 90 point about upon a plane with the burner-cones, and is open at the top. Perforations i may be placed in jacket H, extending from the top 95

thereof to the plane of plate *b*. Upon the interior of jacket *H* may be placed one or more partitions, *h*, extending from the bottom of jacket *H* to a short distance above the top thereof, said partitions *h* extending beneath the burner-cones entirely across the space enclosed by jacket *H*, my said invention being an improvement upon the devices shown in Patent No. 238,395, granted to J. H. Irwin on March 1, 1881, (lamp - stoves,) wherein are shown vertical strips placed against the chimney, forming a support at top for cooking utensils, but extending downward only to the flange upon the burner-cones. Currents of air entering the perforations or passing over the top of jacket *H*, and striking the chimney and flange upon plate *b*, will be deflected downwardly under the plate, and from thence up into the burners. By use of the partitions, no matter from what direction impinging currents may come, they will be deflected thereby in such manner as to promote and accelerate combustion.

The outlet *E'* for the products of combustion in stoves of the construction shown in Fig. 1 is located at the end of the heat chamber or passage opposite to the chimney. It is placed upon the under side of said chamber, so that the products of combustion will be compelled to pass downward in order to escape. Any disturbance of the extraneous atmosphere serves to increase the outflow, thereby promoting combustion at the burners by reason of the increased draft.

In Fig. 1 the direction of the fresh-air currents is indicated by the sharp-headed arrows, and the products of combustion by those having round or blunt heads.

Upon the top of support *F* are placed arms *f*, secured to the edges of outlet *E'*, said arms being of such size as not to interfere with the operation of the stove. If desired, instead of locating a single support in the center of the outlet, two may be used, one upon each side, thereby giving greater strength and solidity to the structure.

For convenience in use, a light shelf, *a*, constructed of perforated metal, wire, or any preferred material, may be located between the oil-pot and top of the stove, as shown. This shelf rests upon a bracket or brackets on support *F*, and upon the top of jacket *H*, or suitable brackets on chimney *E*. If required, several shelves may be employed, the same being made removable from the stove, and in no wise interfering with the operation thereof. In practice they will be found of great convenience, serving as a receptacle for cooking utensils when not in use, as a space for the purpose of keeping articles of food warm when not immediately required, and as a desirable place to set bread, &c., to raise before baking.

Fig. 3 shows a double stove, which may be constructed upon the same principles and operate the same as that shown in Fig. 1, the essential difference being in the provision of two

or more hot-air spaces or passages, with an outlet for the products of combustion at the extremity of each, the burner or burners being located midway between said outlets, and in the use of a series of flanges or divisions, *M*, around the burners. These divisions extend beneath the burner-cones and down to the top of the oil-pot, or to a suitable plate located thereabove, and may be carried up upon the exterior of the chimney to the bottom of base *D'*, as indicated by the dotted lines, Fig. 3, or to any desired height above the plane of the burner-cones.

m is a perforated band extending at an angle from the flange upon plate *b* to the oil-pot or support of the flanges *M*. Currents of air striking these divisions or flanges and the chimney will be deflected to the under side of the burner-cones, and by passing through the perforations in band *m* will feed the flame in a substantially uniform and regular manner. This large form of stove, with any of the air-regulating devices applied thereto, is desirable where great heating-surface or large space for cooking utensils is required.

At a convenient point in the chimney of the stove may be placed a door of suitable size and construction, for the purpose of trimming the wicks, lighting the same, or for reaching the burners for any other purpose, and each oil-pot should be provided with a filler of any approved pattern, for the purpose of supplying the burning-fluid.

Stoves of any size may be constructed in accordance with the foregoing descriptions, and they will be found to admirably answer the various uses and purposes for which they are intended. The locations and arrangement of the inlets for fresh air and the outlets for the products of combustion are such that the stove may be placed in a draft or current of air or used in any exposed position, such currents or drafts serving to promote rather than retard combustion, thus preventing smoking.

Having now fully described my invention, what I claim as new therein, and desire to secure by Letters Patent, is—

1. In a stove of the character herein specified, the combination, with the burners *C*, of plate *b*, partitions *h*, extending beneath the burner-cones, and the jacket *H*, surrounding the burners and base of the chimney at some distance therefrom, the top of said jacket being located nearly upon a level with the burner-cones, substantially as shown and described.

2. In a stove of the character herein specified, the combination, with burners *C*, of jacket *H*, closed at bottom and perforated at its upper edge, and the partitions *h*, extending beneath the burner-cones, substantially as shown and described.

3. The combination, with the burners of an oil-stove surrounded by a jacket open at top, of the partitions located in said jacket, said partitions extending slightly above the jacket and beneath the burner-cones, the whole form-

- ing fresh-air conduits to the under side of the burner-cones, adapted and arranged to conduct fresh air thereto to support combustion, substantially as shown and described.
- 5 4. In a stove of the character herein specified, the combination, with the straight jacket H, closed at bottom and open at top, said jacket being perforated at its upper edge, of the partitions located in said jacket, extending beneath the burner-cones and slightly above the jacket, substantially as shown and described.
- 10 5. In a stove of the character herein specified, the flanges or divisions located upon the outside of the burners, extending beneath the burner-cones and from the oil-pot above the burners upon the exterior of the chimney, substantially as and for the uses and purposes shown and described.
- 15 6. In a stove of the character herein specified, the combination, with the burners surrounded by a jacket closed at bottom and open at top, and having partitions therein extending above said jacket and beneath the burner-cones, of a chimney above said burners, communicating with a hot-air conduit located thereabove, substantially as shown and described.

In testimony that I claim the foregoing I have hereunto set my hand in the presence of two witnesses.

LEWIS F. BETTS.
